UNITED STATES PATENT OFFICE.

WILLIAM E. SMITH, OF MILLTOWN, NEW JERSEY, ASSIGNEE TO KILBOURN MANUFACTURING CORPORATION, OF NEW BRUNSWICK, NEW JERSEY, A CORPORATION OF NEW JERSEY.

CIRCULAR-KNITTING MACHINE.

1,145,930.

Specification of Letters Patent. Patented July 13, 1915.

Application filed July 2, 1914. Serial No. 848,528.

To all whom it may concern:

Be it known that I, WILLIAM E. SMITH, a citizen of the United States, residing at Milltown, in the county of Middlesex and 5 State of New Jersey, have invented certain new and useful Improvements in Circular-Knitting Machines; and I do hereby declare the following to be a full, clear, and exact description of the invention, such as will 10 enable others skilled in the art to which it appertains to make and use the same.

My invention consists in the novel features hereinafter described, reference being had to the accompanying drawings 15 which illustrate one embodiment of my invention selected by me for purposes of illustration, and the said invention is fully disclosed in the following description and claims.

Referring to the said drawings, Figure 1 represents a vertical sectional view of the needle cylinder and needle actuating cams of a circular knitting machine of the well-known Kilbourn type, having my present 20 invention embodied therein. Fig. 2 is a bottom plan view of the inner and outer cam rings for actuating the web holders or sinkers. Fig. 3 is a detail sectional view of the said cam rings, showing the relation 25 of the sinkers thereto. Fig. 4 is a detail view of one of the sinkers lying adjacent to the needles knitting the front portion of the leg and top of the foot of the stocking. Fig. 5 is a similar view showing one of the 30 sinkers used adjacent to the needles knitting the back portion of the leg, the sole, and the heel and toe pockets. Fig. 6 is a top plan view of the sinker actuating cam rings showing the rings partly broken away, and 35 illustrating a few of the sinkers in position in the grooves of the nosing. Fig. 7 is a side elevation of the sinker actuating cam rings.

In the operation of circular knitting machines which are provided with radially movable web holders or sinkers, and which are constructed for both circular and reciprocating work, it is found that during reciprocating work, when the needle actuating 40 cams are operating upon only those needles which knit the rear half of the leg, the sole, and the heel and toe pockets while the remaining needles of the circular series remain stationary and hold the stitches of the

last preceding course of circular work, the 55 reciprocation of the sinker actuating cam ring which accompanies the reciprocating knitting has the effect of slightly moving certain of the sinkers lying adjacent to or between the needles which have been thrown 60 out of operation and are holding their stitches. The effect of this is to cause the said sinkers adjacent to or between the stationary needles, which are so operated, to press upon and recede from the stitches held 65 on the stationary needles adjacent thereto, with the effect of straining and weakening the yarn forming such stitches. Sometimes the stitches are actually broken, but more often they are merely weakened so that after 70 the stocking is knit and has gone into the market, these stitches tend to break and injure the stocking, and cause dissatisfaction on the part of the purchaser. This difficulty has resulted in injury to thousands of 75 pairs of stockings knit on the class of circular knitting machines under consideration, and as the trade is now demanding, and manufacturers are furnishing hosiery in which the front part of the leg and top 80 of the foot, which is knit by the series of needles thrown out of operation during reciprocating work, is formed of extremely fine yarn so as to make an almost transparent fabric, any wear on the stitches formed 85 of this extremely fine yarn is extremely objectionable and likely to cause serious injury to the resulting fabric.

The object of my present invention is to provide a construction which will positively 90 hold stationary all of the sinkers adjacent to the needles which are thrown out of operation during reciprocating work, and prevent any movement whatever of such sinkers, so that the stitches on the stationary needles are relieved from this undue strain and wear. To this end I provide two 95 separate sinker actuating cam rings, one of which operates upon the sinkers adjacent to and between the needles which are operative 100 during reciprocating work, and the other of which operates upon the sinkers adjacent to and between those needles which are held stationary during reciprocating work, and I provide means whereby at the beginning of 105 reciprocating work the latter sinker cam ring is moved to such position that it will not be further operated at all during re-

ciprocating work, thus permitting it to hold its sinkers absolutely stationary during the entire time that the machine is reciprocating, and until circular work is resumed.

5 In the embodiment of my invention herein shown, which I have selected for purposes of illustration, I have shown my invention applied to a circular knitting machine of the well known Kilbourn type, such, for example, as is covered by U. S. Letters Patent #1,087,854, dated Feb. 24, 1914, in the names of E. E. Kilbourn, W. E. Smith, and I. W. Kilbourn. In this type of machine the needle cylinder is stationary and the needles are actuated by two rotary canis arranged one above the other, the needles which knit the front part of the stocking being provided with nibs engaging the lower cam cylinder, and the needles which knit the back half of the stocking being provided with nibs which engage the upper cam cylinder. In the accompanying drawings, I have shown so much of such a knitting machine as is necessary for an understanding of my present invention.

In Fig. 1, which illustrates a sectional view through the knitting head, 1 represents the knitting cylinder which is supported in any desired manner and provided with 30 grooves or tricks in which the needles 2 slide vertically. I prefer to form the needles in two parts, the upper part being the needle proper, and the lower part being what I term a jack, illustrated at 2^a, and having a notched portion to engage a projection on the foot of the needle 2, although the needles might be made in one piece if desired, and as illustrated in the patent heretofore referred to. In this instance the jacks 2 slide vertically in the lower portion 1^a of the needle cylinder, the jacks of those needles knitting the rear half of the stocking being provided with nibs 2^b engaging the upper cam 3, while the jacks of the needles knitting the front portion of the stocking are provided with nibs 2^c which engage the lower cam cylinder 4, suitable means being provided for rotating the cam cylinders together for circular work and for reciprocating the upper cam cylinder only during reciprocating work, such mechanism being well known and forming no part of my present invention.

5 represents what I term the nosing which is provided with radial tricks or grooves to receive the web holders or sinkers 7 and 8, the sinkers or web holders 7 being located adjacent to and between the needles knitting the rear half of the stocking and actuated by the upper cam cylinder 3 and the sinkers 8 being located adjacent to and between the needles knitting the front half of the stocking and actuated by the lower cam cylinder 4.

9 and 10 represent two actuating cam rings

mounted rotatably upon the nosing 5, the cam ring 9 being concentric with and located within the cam ring 10, as clearly shown in Figs. 2, 3, and 6. The cam ring 9 is provided with an annular groove 9^a having a cam portion 9^b, and the cam ring 10 is provided with a similar groove 10^a having a cam portion 10^b, the said cam portions being constructed to give the desired horizontal reciprocation to the sinkers or web holders. Each of the web holders 7 is provided with a vertically disposed nib 7^a which engages the groove 10^a in the outer cam ring 10 and each of the sinkers 8 is provided with a nib 8^a which engages the groove 9^a in the inner cam ring 9, the said nibs and grooves being so constructed that the web holders are held in proper position and are given their desired reciprocating movements. Each of the web holders is provided with the usual guiding recess 7^b and 8^b respectively at its inner end to engage a retaining ring (not shown), and I prefer to provide each of the sinkers with a groove (7^c and 8^c respectively) at its outer end, which latter grooves are engaged by an encircling yielding connection 11 preferably in the form of a very fine spiral spring extending entirely around the series of web holders, and having its ends connected so that the spring, which is under slight tension, tends to hold all of the sinkers in and move them to their inner positions, said sinkers or web holders being moved outwardly only by the cam. The spring may however be dispensed with and both the inward and outward movements of the sinkers or web holders be produced by the engagement of the sinker nibs and cam portions 9^b and 10^b of the respective cam rings. Mechanism is provided for imparting the desired rotary motion to both of these cam rings 9 and 10 during circular work and to the cam ring 10 only during reciprocating work, which may be of any desired character which will accomplish this result. In the present instance I have shown the outer cam ring 10 provided with lugs 10^c carrying adjustable stops 10^d between which lies a bracket or arm 3^a operatively connected with the upper cam cylinder 3, for imparting motion to the outer sinker ring 10 from the upper cam cylinder, and I also provide the cam rings 9 and 10 with co-acting driving lugs or projections, the ring 10 being provided in this instance on its upper face with a horizontal plate 12 extending over the inner ring 9, while the ring 9 is provided with a similar plate 13 extending outwardly over the ring 10 (see Figs. 6 and 7), so that when the outer ring is moved in the direction of the arrow in Fig. 6, the lug 12 will engage the lug 13 and the two rings will move together. The arrow in Fig. 6 represents the direction in which the outer ring 10 is driven from the arm 3^a during circular work

and it will thus be seen that when the machine is operating to produce circular knitting, at which time both cams 3 and 4 are being driven in the same direction, the 5 sinker cam rings 9 and 10 will both be moved simultaneously and circularly in the direction of the arrow. When reciprocating work is commenced, if the ring 9 is not already in position, the first movement of 10 the cam cylinder, if it be in the direction of the arrow in Fig. 6, will carry the inner ring 9 with the ring 10 as far as the movement of the outer sinker ring 10 extends, and as the ring 10 is then moved in the opposite 15 direction, the inner ring 9 will be left stationary and will not be again moved, as will be readily understood, until the reciprocating work is finished and circular work is again resumed, when the circular 20 movement of the outer ring 10 will cause the lug 12 to engage the lug 13 on the inner ring 9 and the two rings will again operate together.

It will thus be seen that during reciprocating work the sinkers or web holders 8 which have their nibs 8^a engaging the inner ring 9 will be positively held from any movement whatever and all the strain or wear upon the threads forming the stitches 30 of the last preceding circular course held on the needles adjacent to said sinkers 8 is avoided, that there is no weakening of the fabric at any point in such course and the objectionable result heretofore referred to 35 caused by the reciprocation of the sinkers effecting a sawing action on the stitches held on the stationary needles is entirely obviated.

While I have shown my invention as applied to a machine of the Kilbourn type in 40 which two separate cams are employed for actuating the needles, I do not limit my invention to this type of machine, as it is equally applicable to other types of machine, in which only a single cam cylinder is employed, and it is also applicable to machines, 45 in which the cam cylinder or cylinders is or are held stationary while the needle cylinder rotates.

What I claim and desire to secure by Letters Patent is:—

1. In a circular stocking knitting machine, the combination with a knitting cylinder, a circular series of needles, and stitch forming needle actuating means, of a series of 50 movable web holders, associated with a portion of the needles, a second series of web holders associated with a second portion of the needles, actuating mechanism for engaging only the web holders of the first mentioned series, separate actuating mechanism for engaging only the web holders of the second mentioned series, and means for throwing one of said separate actuating mechanisms out of operation, whereby 55 neither of said separate actuating mecha-

nisms operatively engages the web holders actuated by the other of said actuating mechanisms.

2. In a circular stocking knitting machine, the combination with a knitting cylinder, a 70 circular series of needles and stitch forming needle actuating means, of a series of movable web holders associated with the needles which remain stationary during reciprocating work, a second series of web holders as- 75 sociated with the needles which are operated during reciprocating work, means operable during circular and reciprocating work for actuating the web holders of the last mentioned series, separate means for actuating 80 the web holders of the first mentioned series, and means for connecting said actuating means for both series during circular work only.

3. In a circular stocking knitting machine, the combination with a knitting cylinder, a circular series of needles and stitch forming needle actuating means, of a series of movable web holders associated with the needles which remain stationary during reciprocating work, a second series of web holders as- 90 sociated with the needles which are operated during reciprocating work, the web holders of each series being provided with actuating nibs, an actuating device operable during 95 circular work only, provided with means for engaging the nibs of the work holders of the first mentioned series, and a separate actuating device operable during circular and reciprocating work for engaging the nibs of 100 the work holders of the last mentioned series.

4. In a circular stocking knitting machine, the combination with a knitting cylinder, a circular series of needles and stitch forming needle actuating means, of a series of movable web holders associated with the needles which remain stationary during reciprocating work, a second series of web holders as- 105 sociated with the needles which are operated during reciprocating work, the web holders of each series being provided with actuating nibs, an actuating cam ring engaging the 110 nibs of the web holders of the first mentioned series only, a second cam ring engaging the nibs of the web holders of the last mentioned series only, means for imparting motion to said second cam ring during both circular and reciprocating work, and means for connecting said rings for joint rotation during circular work only.

5. In a circular stocking knitting machine, the combination with a knitting cylinder, a circular series of needles and stitch forming needle actuating means, of a series of movable web holders associated with the needles which remain stationary during reciprocating work, a second series of web holders as- 120 sociated with the needles which are operated during reciprocating work, the web holders of each series being provided with actuating 125

- nibs, an actuating cam ring engaging the nibs of the web holders of the first mentioned series only, a second cam ring engaging the nibs of the web holders of the last 5 mentioned series only, means for imparting motion to said second cam ring during both circular and reciprocating work, said cam rings being provided the one with a part in the path of a part secured to the other, 10 where by the said parts will engage and secure the joint operation of said cam rings during circular work, and means for rotating said second cam ring during circular work, and for reciprocating said ring during reciprocating work.
6. In a circular stocking knitting machine, the combination with a knitting cylinder, a circular series of needles and stitch forming needle actuating means, of a series of movable web holders associated with the needles which remain stationary during reciprocating work, a second series of web holders associated with the needles which are operated during reciprocating work, the web holders 20 of each series being provided with actuating nibs, an actuating cam ring engaging the nibs of the web holders of the first mentioned series only, a second cam ring engaging the nibs of the web holders of the last 25 mentioned series only, means for imparting motion to said second cam ring during both circular and reciprocating work, said second cam ring being provided with a driving lug, and the first mentioned cam ring being 30 provided with a projection in the path of said driving lug for driving it from the second cam ring during circular work and means for rotating said second cam ring during circular work, and for reciprocating 35 it during reciprocating work.
7. In a circular stocking knitting machine, the combination with a knitting cylinder, a circular series of needles and stitch forming needle actuating means, of a series of movable web holders associated with the needles which remain stationary during reciprocating work, a second series of web holders associated with the needles which are operated during reciprocating work, the web holders 45 being each provided with an actuating nib, the nibs of the web holders of one series being located at a greater distance from the center of the needle cylinder than the nibs of the web holders of the other series, a cam 50 ring provided with a cam groove engaging the nibs of one series of web holders, and a second cam ring of different diameter having a groove engaging the nibs of the other series of web holders, means for securing 55 the operation of one of said cam rings during circular work and reciprocating work, and means for securing the operation of the other cam ring during circular work only.
8. In a circular stocking knitting machine, 60 the combination with a knitting cylinder, a circular series of needles and stitch forming needle actuating means, of a series of movable web holders associated with the needles which remain stationary during reciprocating work, a second series of web holders associated with the needles which are operated during reciprocating work, the web holders being each provided with an actuating nib, the nibs of the web holders of one series being located at a greater distance from the center of the needle cylinder than the nibs of the web holders of the other series, a cam ring provided with a cam groove engaging the nibs of one series of web holders, and a second cam ring of different diameter having a groove engaging the nibs of the other series of web holders, means for securing the operation of one of said cam rings during circular work and reciprocating work, and means for securing the operation of the other cam ring during circular work only.
9. In a circular stocking knitting machine, the combination with a needle cylinder, a circular series of needles, a knitting cam operable during circular and reciprocating work operatively engaging certain of said needles, a separate stitch cam operable during circular work only, operatively engaging the other needles of the circular series, of movable web holders, each provided with an actuating nib, the nibs of the work-holders associated with the needles which remain stationary during reciprocating work being located at a different distance from the center of the needle cylinder from the nibs of the other web holders, two separate cam rings, each having a groove for engaging the nibs of one series of web holders, an actuating part on the reciprocating cam operatively engaging one of said rings for securing its operation during circular and reciprocating work, and operative connections between said rings for securing their joint operation during circular work.
10. In a circular stocking knitting machine, the combination with a needle cylinder, a circular series of needles, a circular series of radially movable web holders, each provided with an actuating nib, the series of web holders associated with the needles which remain stationary during reciprocating work having their nibs at a different distance from the center of the needle cylinder from the nibs of the other series of web holders, two separate cam rings of different diameters, each provided with a cam groove engaging the nibs of the work holders of one series only, means for driving one of said cam rings during circular and reciprocating work, and means for securing the joint operation of said rings during circular work.
11. In a circular stocking knitting ma-

chine, the combination with a knitting cylinder, a circular series of needles, and stitch forming needle actuating means, of a series of movable web holders, associated with a portion of the needles, a second series of web holders associated with a second portion of the needles, said web holders being each provided with an actuating nib, the nibs of the web holders of one series being located at a different distance from the axis of the needle cylinder from those of the other series, 10 separate actuating cams located at different distances from the axis of the cylinder, each constructed to engage the nibs of one series only of said web holders, and means for throwing one of said cams out of operation.

12. In a circular stocking knitting machine, the combination with a needle cylinder, a circular series of needles mounted therein, and stitch forming needle actuating means, of a series of radially movable web holders associated with a portion of the needles, and a second series of movable web

holders associated with another portion of the needles, all of said web holders being provided with actuating nibs, the nibs of one series of web holders being located at a different distance from the axis of the needle cylinder from those of the other series, 30 a cam ring simultaneously engaging the nibs of one series of web holders only, a separate cam ring simultaneously engaging the nibs of the other series of web holders only, means for establishing relative rotation between the needle cylinder and cam rings, and means for permitting one of said cam rings to remain stationary with respect to the needle cylinder, and thereby hold all the web holders of the series engaged and 35 operated by it from radial movement.

In testimony whereof I affix my signature, in the presence of two witnesses.

WILLIAM E. SMITH.
